UNITED STATES PATENT OFFICE.

PAUL H. BRANDT, OF CLEVELAND, OHIO, ASSIGNOR TO THE TEAGLE COMPANY, OF CLEVELAND, OHIO, A CORPORATION OF OHIO.

IGNITION-GENERATOR.

1,367,586.

Specification of Letters Patent. Patented Feb. 8, 1921.

Application filed August 23, 1917. Serial No. 187,790.

To all whom it may concern:

Be it known that I, PAUL H. BRANDT, a citizen of the United States, residing at Cleveland, in the county of Cuyahoga and 5 State of Ohio, have invented certain new and useful Improvements in Ignition-Generators, of which the following is a specification, reference being had therein to the accompanying drawing.

10 This invention relates to improvements in electric generators for ignition purposes, and is especially applicable to ignition generators of the inductor alternator type.

The provision of a suitable spark range 15 in inductor generators limited in dimensions to the standards now generally fixed for internal combustion engine ignition generators presents a problem difficult of satisfactory solution. Numerous constructions designed to effect relative angular movement 20 between the unwound rotor of the inductor generator and a normally stationary stator carrying a generating winding, have been tried out, all of which so far as I am advised 25 have possessed numerous inherent disadvantages. It has been suggested to mount the normally stationary stator so that it may be turned about the axis of the unwound rotor to secure the desired advance or retard of 30 the generated current waves. However, not only has it been found difficult to mount the stator effectively and economically to allow for such swinging, but the electro-magnetic impulses on the stator thus swingably 35 mounted, which occur periodically during the rotation of the unwound rotor tend to impose harmful vibrations not only on the stator and its mountings but particularly upon the necessary train of members by 40 which the stator is adjusted. Furthermore, such stators necessarily possess considerable mass and it is disadvantageous to have this mass free to swing about the axis of the unwound rotor.

45 It further has been suggested to swing both the field magnet, generating winding and pole pieces about the axis of the unwound rotor, but this idea is essentially impractical because of the fact that the field magnet mass is unbalanced relative to the axis about which it is swung, the oscillatory vibrations set up are highly objectionable and the requirements for space necessary to permit the swinging are difficult to provide

where the usual standard conditions obtain 55 for the mounting of ignition generators on internal combustion engines.

Again, it has been suggested to connect the rotor at a point outside the ignition generator to a driving shaft by a connecting 60 mechanism which will permit the rotor as an entirety to be turned angularly relative to the driving shaft while it is turning the rotor. Owing to the mass of the rotor, the stresses placed on an angular adjusting 65 mechanism of this sort have been found to be very severe and the wear and tear to be so considerable as to effect lost motion between the parts of the adjusting mechanism within a relatively short period of time. 70

Further, it has been suggested to interpose between the field structure carrying the stationary generating winding and the rotatable unwound inductor an oscillatable sleeve having magnetic and non-magnetic 75 sections for field flux shifting purposes. The expense of such constructions, together with the undesirable reluctances imposed by them in the magnetic circuit, among other characteristics, have made them commercially undesirable. 80

I have thought to solve the problem by reducing to a minimum the mass of metal which is angularly adjusted about the axis of the unwound rotor in order to effect the 85 desired advance and retard of the generated current waves, and with this object in view I have provided means for mounting the flux distributing part of the unwound inductor rotor loosely upon the shaft of such rotor and connecting it with the said shaft by a suitable device which will cause the flux distributing section always to turn with the rotor, whereas by a relative shifting of elements comprising said device the flux dis 90 tributing section may be caused to turn angularly relative to the rotor shaft to effect the desired advance or retard of the current waves simultaneously with the advance or 95 retard of the spark. 100

My invention further contemplates a simple form of circuit opening and closing mechanism adapted to be associated with a cam on a rotating shaft of the ignition generator and constructed so that (1) the breaker electrodes are disposed at one side of the generator where they may be readily inspected, (2) the parts comprising the cir-

cuit opening and closing mechanism are assembled as a unit, which unit may be slid longitudinally into and out of operating position within the ignition generator, and 5 (3) this unit may be introduced from either side of the ignition generator, readily to accommodate the same for either clockwise or anticlockwise rotation of the unwound rotor

10 For the purpose of clearly explaining the invention and the manner in which its objects may be attained, I have illustrated a preferred form of construction in the accompanying drawings. In said drawings:

15 Figure 1 is a central longitudinal vertical section of a generator embodying my invention.

Fig. 2 is a transverse section on the broken line 2—2 of Fig. 1.

20 Fig. 3 is an axial section of one of the parts of the mechanism.

Fig. 4 is a transverse section on the broken line 4—4 of Fig. 1.

25 Figs. 5 and 6 are side and end elevations, respectively, of one of the parts of the mechanism.

Referring in detail to the construction illustrated, 1 indicates a lower pole piece and 2 an upper pole piece, each of which 30 may be made of any suitable magnetic material. The pole piece 1 is formed with a polar surface 1' and the pole piece 2 carries polar projections 2', 3, the former of which has a polar face 2^a and the latter 35 a polar face 3^a, each of which is opposed to the polar face 1' of the pole piece 1, while all three faces are disposed in the arc of a common circle. The polar projection 3 may consist of a plurality of laminæ of soft 40 iron held together by side plates 4, 4', and rivets 4^a. At their upper ends the side plates 4, 4', extend beyond the upper edge of the adjacent laminations and snugly fit over the projection 2^b of the upper pole 45 piece and are secured to the latter by means of bolts 5. The surfaces 2^c and 2^d of the portion 2^b may be suitably ground or made relatively true mechanically so as to come 50 into intimate mechanical contact with the adjacent edges of the laminations of the polar projection 3 to insure a joint of relatively low magnetic reluctance.

6 and 7 are end plates, each formed of 55 non-magnetic metal, such as die cast white metal or metallic alloy of aluminum. The end plate 6 may be secured to the pole pieces 1 and 2 in any suitable manner and may be provided with shoulders 6', 6^a, in order to insure the proper relation of these parts.

60 Likewise the end plate 7 may be secured to the lower and upper pole pieces 1 and 2, respectively, in any suitable manner and may be provided with shoulders 7', 7^a, for insuring the proper positioning of these parts.

65 In the construction shown the end plates are

secured by bolts 6^b, which pass through both end plates and the pole piece 1, and bolts 6^c which pass through both end plates and the pole piece 2. It will be noted that when the four elements comprising the pole pieces 7^a 1 and 2 and the end plates 6 and 7 are secured together, they form substantially a rigid, rectangular frame structure.

8 indicates a flux distributor, preferably formed of laminæ of soft iron and having 75 polar surfaces 8', 8^a, shaped and disposed to coöperate with the polar surfaces 1', 2^a, and 3^a. This flux distributing section 8 is loosely mounted upon a shaft 9 which in turn is suitably mounted in anti-friction bearings 10 and 11, the former being suitably supported in the end plate 6 and the latter in the end plate 7. 12 indicates as an entire means interposed between the flux distributor 8 and the shaft 9 for causing 80 the flux distributor to rotate with the shaft 9 while permitting it to be adjusted angularly relatively thereto. Preferably this flux distributor connector and shifter mechanism 12 comprises a sleeve 12' loosely 90 mounted on the shaft 9 and having a flange 12^a which is rigidly secured to the flux distributor 8 in any suitable manner, as by means of the rivets 13, which also serve to bind together between the side plates 8' and 8^a, the laminæ which constitute the flux distributor. At 12^b the sleeve 12' is preferably reduced in diameter and mounted within the inner race of the anti-friction bearing 11, so that whereas it has heretofore been 100 stated that the shaft 9 is mounted in the bearing 11, it is indirectly mounted therein, having interposed between it and the inner race of the bearing the portion 12^b of the sleeve 12'. The sleeve 12' is further 105 reduced in diameter as indicated at 12^c and helically grooved internally as indicated at 12^d. The rear end of the shaft 9 is reduced in diameter as indicated at 9^a, and longitudinally key-seated as indicated at 9^b, 110 there preferably being a plurality of these key seats disposed about the periphery of the reduced portion 9^a and parallel to the axis thereof.

14 is a shiftable sleeve formed internally 115 with a plurality of keys 14', each of which is adapted snugly to fit into one of the key ways 9^b in the reduced portion 9^a of the rotor shaft 9. Externally this sleeve 14 is formed with a plurality of helical tongues 120 or splines 14^a, each of which is adapted snugly to fit into one of the helical grooves 12^a in the sleeve 12'. 15 is a grooved wheel rigidly secured to the outer end of the sleeve 14 in any suitable manner.

9' is a collar on the shaft 9, engaging at one side with the inner ring of the anti-friction bearing 10 and at its other side with the adjacent end plate 8' of the flux distributor 8. 11' is a screw-threaded collar 130

fitted into a screw-threaded recess in the end plate 7 and 11^a is a similar collar on the sleeve 12', said collars serving properly to position the anti-friction bearing 11. 16 is 5 a gear wheel fitted upon the reduced section 12^c of the sleeve 12 and secured to turn therewith in any suitable manner. 17 is a cam fitted upon the reduced section 12^c of the sleeve 12', and suitably secured to turn 10 therewith, the cam being secured against endwise movement by a nut on the sleeve 12'. It will be noted that longitudinal movement of the shaft 9 toward the bearing 10 is prevented by engagement of the collar 9' with the inner wall of said bearing, 15 whereas longitudinal movement of the shaft 9 in the opposite direction is prevented by engagement of the said shaft with the shoulder 12^e on the sleeve 12'. Longitudinal movement of the flux distributer 8 and sleeve 12' toward the bearing 10 is precluded by the shoulder 9' on the shaft 9, whereas the longitudinal movement of these parts in 20 the opposite direction is precluded by the engagement of the shoulder 12^e on the sleeve 12' with the inner race of the anti-friction bearing 11.

The end plate 7 at its bottom has a forward extension 7^b. 19 is a casing secured to the extension 7^b as by means of cap screws 19^a, and having a chamber 19' disposed to receive the free end of the sleeve 14 and the shifting wheel 15 thereon. 20 is a rock shaft suitably mounted in the upper part of the 35 casing 19. It carries within the casing a plurality of rocker arms 21, 21, connected by a tubular section 22 with which they are preferably integrally formed. 23 is a cap screw and pin for securing the tubular section 22 to the rock shaft 20. At its lower end each rocker arm carries an antifriction roller 24 disposed within the flanges of the wheel 15 in the well known manner, so that when the rocker arms 21 are swung toward 40 the flux distributer 8 they engage the innermost pulley flange and exert inward pressure on the said pulley, whereas when they are swung away from the flux distributer they engage the outer pulley flange and 45 force the pulley and sleeve 14 outwardly. Each of the rollers 24 is loosely mounted on a stud 25 carried by the adjacent rocker arm. The rock shaft 20 extends outside of the casing 19 and preferably has secured to one 50 end thereof an operating lever 26.

28 indicates as an entirety circuit closing and opening mechanism preferably assembled as a unit to be inserted into or withdrawn from operative relation with the cam 60 17 by endwise bodily movement of said unit. This breaker unit comprises a frame 28' in the form of a slide having intermediate its 65 ends a pair of upwardly turned ears 28^a, a breaker arm 28^b pivotally mounted between said ears 28^a on a rod or shaft 28^c, a movable

electrode 28^d carried at one end of said breaker arm, a cam engaging shoe 28^e carried at the other end of said arm, a breaker arm spring 28^f and a normally stationary adjustable electrode 28^g disposed in the path 70 of movement of the movable electrode 28^d and suitably insulated, as indicated, from the slide 28'. The shoe 28^e may be made of fiber or any other suitable wear resisting material for engagement with the surface of 75 the cam 17. The spring 28^f may be of any suitable construction. I have shown it to be a flat spring connected at 28^h to a lug on the slide 28' and at 28ⁱ to the breaker arm, the tendency of this spring being to swing the 80 movable electrode 28^d into engagement with the normally stationary electrode 28^g. This slide 28' is fitted into a guide or seat 7^d formed in the extension 7^b of the front plate 7. Preferably the slide is held in position 85 within the guide so that the shoe 28^e will be in proper cooperative relation with the cam 17 by means of the screws 19^a, 19^b, which are also used to hold the casing 19 in position.

The end plate 7 has openings 7^e at opposite sides of the forward extension 7^b through which it is possible to insert and withdraw the breaker unit 28 in either direction. It will be noted that not only may the 90 unit 28 be inserted from either side of the extension 7^b, but it also may be inserted with the breaker electrodes at either side of the vertical plane through the axis of the rotor, so as to accommodate the breaker for proper 95 operation with the cam 17 in either direction 100 of rotation thereof, that is clockwise or anti-clockwise.

In other words the same breaker assembly 105 can as a unit, be used interchangeably on generators operating in either clockwise or counter-clockwise directions. The advantages of this in manufacture are obvious.

Any suitable distributer mechanism may be employed in connection with the ignition generator. For the purpose I have illustrated one which is designated as an entirety 110 by 30. It comprises a distributer cap 30' of suitable insulating material which carries a plurality of distributer contacts 30^a from each of which a high tension lead 30^b extends 115 in the well known manner. This distributer cap 30' may be fitted to the end plate 7 in any suitable manner so as to be readily detachable for inspection purposes. This connection I have shown to be accomplished at 120 the top of the distributer cap by means of a pivoted bolt 30^c and at the bottom thereof by means of screw clamps 30^d. 30^e is a distributer brush suitably mounted in a rotatable block 30^f of insulating material, which 125 brush is electrically connected to the brush 30^g in any suitable manner as by means of the metallic socket 30^h and metallic piece 30^k, which latter is carried in the hub of the 130 section 30 of insulating material. 30^m is a

section of insulating material having a hub section to receive the hub of the section 30^f and at its inner end an insulating flange. 31 is a distributor gear meshing with the 5 gear 16 on the sleeve 12 and having a hub 31' which firmly engages the hub of the insulating section 30^m. The gear 31 may be secured to the sections 30^f and 30^m in any well known manner. This hub 31' is rotatably mounted in a bearing bushing 32 suitably supported in an enlarged portion 7^e of the front plate 7.

33 is a generating winding. It may be of any desired construction. Preferably it is 15 wound on the polar projection 3, a portion intermediate the ends thereof serving as a laminated core for the winding. The winding is suitably insulated in any well known manner and when the polar projection 3 is 20 connected to the pole piece 2, the winding 33 is properly disposed in inductive relation in the magnetic field between the poles 1 and 2. This winding 33 I have shown to be 25 constituted of a relatively coarse wire, or primary section, 33', surrounded by a section of relatively fine wire, or secondary winding, 33^a. One terminal of the winding 33^a is electrically connected to a terminal 34 with which engages the brush 30^g. The 30 terminal 34 may be extended upwardly, as indicated at 34', so as to form between the free end thereof and an adjacent metallic part of the generator, such as one of the bolts 5, a safety air gap for the high tension 35 circuit.

The other end of the secondary winding 33^a and one terminal of the primary winding 33' are electrically connected in the usual manner to each other and to an electric conductor which extends to and is electrically connected with the normally stationary electrode 28^e. The other end of the primary winding 33' and also the movable electrode 28^d are suitably grounded.

45 35 is a condenser of any suitable construction which may be suitably positioned and held in a recess 7^f in the end plate 7. This condenser is connected in parallel across the electrodes 28^d and 28^e, in the usual manner.

50 All of the parts heretofore described may be assembled adjusted and properly correlated before the permanent magnets 36 are introduced into place. Preferably these magnets consist of straight sections of suit-

55 able magnet steel each of which at its upper end makes magnetic contact with the pole piece 2 and at its lower end with the pole piece 1. The magnets are preferably arranged in groups, one group at either side

60 of the field structure, and with all of the poles of one polarity in magnetic contact with one pole piece and all of the poles of opposite polarity in contact with the other pole piece. For example, all of the north 65 poles of the magnets at either side of the

pole piece 2 will be in magnetic contact with said pole piece, whereas all of the south poles of the magnet will be in magnetic contact with the pole piece 1. The magnets may be held in position in any suitable manner, 70 as by means of screws 37 which extend therethrough and are fitted into the adjacent pole piece.

The casing 19 may be provided with a cap 19^b suitably held in position thereon. An 75 oil duct 19^c may extend downwardly through the cap 19^b and casing 19 and have an inward extension 19^d along the axis of the rotor, the inner end of the duct 19^c being disposed so as to deliver oil to the interior 80 of the sleeve 14 to insure the proper lubrication thereof. The oil may collect in the chamber 19 so that the wheel 15 runs therein and distributes it over the anti-friction rollers 24 and also onto the sleeve 14 so as to 85 insure the proper lubrication of the sleeve 14 within the sleeve 12'. The sleeve 12' is preferably made of non-magnetic material, such as brass, and the sleeve 14 may be made either of magnetic or non-magnetic material, 90 as desired.

The end 9^a of the shaft 9 is shaped to be connected with any suitable driving mechanism so as to be continuously rotated in one direction thereby during the operation of the 95 ignition generator. The angle of the helical grooves 12^a and splines 14^a is such that when the sleeve 14 is rotated in either direction by the shaft 9, the sleeve 12' will be rotated in the same direction, whereas if it is desired 100 to adjust the flux distributor 8 angularly in either direction in relation to the shaft 9 during the rotation of the latter, and simultaneously with the advance or retard of the spark the same is accomplished by moving 105 axially in one direction or the other the sleeve 14 through the instrumentality of the anti-friction rollers 24 and wheel 15, which longitudinal movement of the sleeve 14 will, through the helical splines 14^a and grooves 110 12^b, effect the desired angular swing of the flux distributor 8 and the breaker cam 17 relative to the shaft 9. The mass of the flux distributor 8 and sleeve 12' may be maintained relatively low, so that the amount of 115 energy necessary to effect the angular shifting of these parts in either direction is relatively small.

The operation of my improved generator 120 will readily be understood without an extended description. Assuming movement of the rotor in the direction indicated by the arrow in Fig. 2, it will be seen that the flux distributor 8 distributes the magnetic flux alternately through the polar projections 3 125 and 2'. As the flux distributor is bi-polar it causes the flux through the polar projection 3 which carries the generating winding to alternately increase and decrease twice during each rotation of the distributor. The 130

5 circuit opening and closing mechanism 28, operating in timed relation to the movement of the flux distributor, serves to close and open the circuit through the coarse section 10 of the generating winding at suitable points to effect generation of the high tension ignition current; preferably the said circuit is closed and opened during decrease of flux through the generating winding, the circuit 15 being opened for the production of the high tensioned current when the decrease of flux is at its maximum. The collapse of the field through the generating coil due to the opening of the coarse wire circuit and the rotation 20 of the flux distributor serve to generate a high tension ignition current in the fine wire section of the winding in a well known manner. The distributor 30, operating synchronously with the flux distributor and 25 the breaker cam, serves in the well known manner to conduct the high tension current to one or another of the spark plugs of the engine in connection with which the generator is used.

25 When, under the various conditions of operation, it is desired to advance or retard the spark, this is effected by simply shifting the operating lever 26 and thereby correspondingly shifting the sleeve 14 endwise so as to 30 adjust the sleeve 12' forwardly or backwardly on the shaft 9. This adjustment of the sleeve 12' effects corresponding angular adjustment of the flux distributor 8 and the cam 17, so that with the advance and retard 35 of the spark the flux distributor is simultaneously adjusted to maintain the generation of the ignition current at the point of maximum voltage.

Should it be desired to adapt the breaker 40 mechanism for operation of the generator in the opposite direction from that indicated in Fig. 2, it is only necessary to remove the slide 28' of the breaker mechanism and the parts mounted thereon, and replace 45 it in reverse position.

The device which I provide for the adjustment of the flux distributor accomplishes the desired object in a thoroughly effective manner and because of the relatively light weight of the parts adjusted 50 and the large bearing surfaces of the several splines and grooves by which the train of adjusting elements are connected, shock and vibration are reduced to a minimum. Furthermore, the structure is exceedingly 55 compact, the overall dimensions of the generator being little different from those of a generator without the adjusting feature, and at the same time it has the advantage of 60 a self-contained unit.

It is to be understood that the construction illustrated can be varied widely without departing from my invention, the particular construction shown having been set 65 forth for purposes of explanation and with-

out the intention of in any way limiting the invention.

What I claim is:

1. In an inductor ignition generator, the combination of a stationary field structure, 70 a stationary generating winding disposed in inductive relation to said field structure, a shaft rotatably mounted in said field structure, an unwound flux distributor loosely mounted on the shaft, a sleeve rigid with 75 the flux distributor and loosely mounted on said shaft, a cam rotatable with the sleeve, means connecting the sleeve and shaft to cause them to rotate together and permit the sleeve to be adjusted angularly relatively to the shaft to advance or retard the flux distributor and cam simultaneously, and circuit opening and closing mechanism for the generating winding arranged to be 80 actuated by said cam. 85

2. In an inductor ignition generator, the combination of a stationary field structure, 90 a stationary generating winding disposed in inductive relation to said field structure, a shaft rotatably mounted in said field structure, an unwound flux distributor loosely mounted on the shaft, a sleeve rigid with 95 the flux distributor and loosely mounted on said shaft, a driving device between the shaft and sleeve having an axially elongated tongue and groove connection with the shaft and the sleeve, one of said tongue and groove connections being helical, and means for shifting said driving device longitudinally of the shaft to angularly advance or 100 retard the sleeve and flux distributor relative to the shaft. 100

3. In an inductor ignition generator, the combination of a stationary field structure, 105 a stationary generating winding disposed in inductive relation to said field structure, a shaft rotatably mounted in said field structure, an unwound flux distributor loosely mounted on the shaft, a sleeve rigid with 110 the flux distributor and loosely mounted on said shaft, a second sleeve keyed to said shaft to slide longitudinally thereon and having a helical tongue and groove connection with the first named sleeve, and means for shifting the keyed sleeve longitudinally of the shaft to advance or retard 115 the flux distributor in relation thereto. 115

4. In an inductor ignition generator, the combination of a stationary field structure, 120 a stationary generating winding disposed in inductive relation to said field structure, a shaft rotatably mounted in said field structure, an unwound flux distributor loosely mounted on the shaft, a sleeve rigid with 125 the flux distributor and loosely mounted on said shaft, a second sleeve keyed to said shaft to slide longitudinally thereon and having a helical tongue and groove connection with the first named sleeve, a wheel on the outer end of the keyed sleeve, an oil 130

chamber surrounding said wheel, and means disposed in said chamber for moving the wheel axially.

5. In an ignition generator, the combination of a frame structure formed with a seat, a cam mounted to rotate in said frame structure in transverse alinement with said seat, and a circuit closing and opening mechanism comprising a frame formed to 10 fit said seat, a stationary electrode member mounted on the second frame, a movable electrode member mounted on the second frame and having a cam engaging surface, and means for holding the second frame in 15 said seat in coöperative relation to the cam.

6. In an ignition generator, the combina-

tion of a frame structure formed with a seat, a cam mounted to rotate in said frame structure in alinement with said seat, and a circuit closing and opening mechanism comprising a second frame formed to fit the seat, a stationary electrode on the second frame, a breaker arm with an electrode and a cam engaging shoe mounted on the second frame, said second frame and parts thereon 20 being reversible as a unit relative to the seat so as to locate the said shoe at either side of the axis of the cam to adapt the mechanism for rotation of the cam in either direction.

In testimony whereof I hereunto affix my 30 signature.

PAUL H. BRANDT.
